MATERIAL STEAMER

Norman H. Warring, 24737 Calvin, Dearborn, Mich.
Filed June 18, 1959, Ser. No. 821,146

2 Claims. (Cl. 34—73)

This invention relates generally to material steaming apparatus, and, more particularly, to a new and improved apparatus for steaming wood and the like for preparing and softening the same for the purpose of bending it into a desired shape.

It is an important object of this invention to provide a material steaming apparatus which is especially adapted for steaming pieces of wood, as ship ribs and the like, and which is constructed to permit quick and easy movement thereof from one place of use to another.

It is another object of this invention to provide a material steaming apparatus of the class described which is simple and compact in construction, portable, economical of manufacture, and efficient in operation.

It is still another object of this invention to provide a material steaming apparatus which is especially adapted to steam wood pieces such as boat ribs and the like and which includes means for supporting the material being steamed with said means being adapted to be releasably secured to the material to be steamed before being mounted in the steaming apparatus.

Other objects, features and advantages of this invention will be apparent from the following detailed description and appended claims, reference being had to the accompanying drawing forming a part of the specification wherein like reference numerals designate corresponding parts of the several views.

In the drawing:

FIG. 1 is a side elevational view of a material steaming apparatus made in accordance with the principles of the invention;

FIG. 2 is an enlarged front end elevational view of the structure illustrated in FIG. 1 taken along the line 2—2 thereof and looking in the direction of the arrows;

FIG. 3 is a partial elevational longitudinal sectional view of the structure illustrated in FIG. 2 taken along the lines 3—3 thereof and looking in the direction of the arrows; and,

FIG. 4 is an elevational sectional view of the structure illustrated in FIG. 1 taken along the line 4—4 thereof and looking in the direction of the arrows.

Referring now to the drawings, and in particular to FIG. 1, the material steaming apparatus of the present invention comprises the tubular body 10 which may be made from any suitable material and which is enclosed at the rear end thereof by the plate 11. The plate 11 is fixedly secured to the body 10 by any suitable means as by welding. As shown in FIGS. 1 and 2, the open front end of the body 10 is adapted to be closed by the removable cap structure generally indicated by the numeral 12. The body 10 is supported by means of a pair of legs generally indicated by the numerals 13 and 14 with the front leg 14 being at least one inch shorter than the rear leg 13 to permit drainage towards the front end of the body 10. The legs 13 and 14 are similarly constructed and the construction of the leg 13 is fully shown in FIGS. 1 and 4. The leg 13 comprises a horizontal ground engaging bight portion 15 from the ends of which extend upwardly the vertical leg portions 16 and 17. The upper ends of the leg portions 16 and 17 are swingably mounted on the horizontally disposed outwardly extended shafts 18 and 19 which are fixedly mounted at the side of the body 10. The legs 13 and 14 are thus seen to be substantially U-shaped in cross section. The leg 14 is constructed similarly to the leg

2

13 and the corresponding parts are marked with small reference numerals followed by the small letter "a."

The cap structure 12 includes the gasket 20 which is adapted to be seated over the open end of the body 10, as shown in FIG. 3. The gasket 20 is held in place on the body 10 by means of a cover member which includes the plate 21 which is provided with the integral annular lip 22 which encloses the gasket 20 and extends longitudinally of the body 10. It will be seen that the annular lip or flange 22 is disposed outwardly from the body 10 to provide a passage for escaping steam as more fully described hereinafter. The cover means 12 further includes a steel band spring 23 which is fixedly secured to the outer face of the cover plate 21 by means of the rivets 24. The cap structure 12 is adapted to be releasably secured on the body 20 by means of a spring wire retainer means which is U-shaped in cross section and which comprises the bight portion 25 and the leg portions 26 and 28. As shown in FIGS. 1, 2 and 3, a spring wire retainer leg 26 is adapted to be swingably mounted on the shaft 27 which is fixedly secured to one side of the body 10. The other leg 28 of the spring retainer means is adapted to be similarly swingably mounted on the shaft 29 which is disposed on the other side of the body 10 at a point diametrically opposite to the shaft 27. It will be seen that the spring retainer means is adapted to have the bight portion 25 engage the steel spring 23 in the centrally disposed concave portion 30 of the spring 23 whereby the cap structure 12 is releasably secured in place on the body 10. The cap structure 12 will be easily and quickly removed from the body 10 for loading purposes by merely swinging the spring retainer means off of the spring 23 and to the side of the body 10. It will also be seen that after the steam pressure builds up in the body 10, the steel spring 23 will flex to permit the gasket 20 and cover 21 to move outwardly from the body 10 to let the steam escape from the body 10 and reduce the pressure therein, and act as a safety valve.

As shown in FIG. 1, the material steamer apparatus 40 of the present invention includes a steam generating means generally indicated by the numeral 31. The steam generating means 31 comprises a short piece of tube which is fixedly secured to the lower side of the body 10 adjacent the front end thereof. The tube 31 communicates with the body 10 from the opening 32 and the lower end of this tube is enclosed. A suitable heating coil, as for example, a 750 watt electrical heating coil 33 is suitably mounted upon the outer surface of the tube 31 and is adapted to be connected to any suitable source of electrical power by means of the lead wires 34 and 35.

As shown in FIGS. 1 and 4, a workpiece as 36 is adapted to be held in the tube 10 for steaming purposes by a plurality of work supporting members generally indicated by the numerals 37, 38 and 39. Each of these work supporting members is constructed in the same manner and only one has been fully shown in FIG. 4. As shown in FIG. 4, the work supporting member 37 is formed from a suitable metal wire like material and includes a lower curved portion 40 which is adapted to be seated on and meet with the lower inner surface of the tubular body 10. The central portion of the part 40 is provided with an upwardly curved form as indicated by the numeral 41 to permit the drainage of water indicated by the numeral 42 to flow back to the steam generating tube 31. The work supporting means 37 further includes the vertical legs 33 and 34 which are integral to the ends of the base portion 40 and which are provided on the upper ends thereof with a wavy portion as more fully explained hereinafter. The work supporting means 37 further includes the transverse cross piece generally indicated by the numeral 35 which is adapted to support the workpiece 36 in a recess 46

formed centrally of the part 45. The workpiece 36 is adapted to be releasably clamped in the recess 46 by means of a clamp wire 47 which is adapted to have the ends thereof twisted around the upper wavy ends of the legs 33 and 34 as shown in FIG. 4. As illustrated in FIG. 1, the body 10 may be provided with a suitable pressure indicating gauge 48, if desired. The body 10 is provided with the vent 49. The legs 13 and 14 are retained in the supporting position by the braces 50 and 51, the upper ends of which are looped around the fixed stud 52 and held thereon by the nut 53. The lower ends of the braces 50 and 51 are looped around the raised portions 55 and 56, respectively, on the legs.

In operation, it will be seen that the material steaming apparatus of the present invention is portable and may be quickly and easily moved about from place to place as desired. The legs 13 and 14 are swingably mounted and may be swung close to the body 10 for packing and travelling purposes. The workpiece 36 would first be mounted on the plurality of the work supporting means as 37, 38 and 39 and then it would be mounted in the tubular body 10. The steam generating tube 31 would then be filled with water and the cap 12 then mounted in place. The lead-wires 34 and 35 are then connected to a suitable source of electrical power and steam will be generated in the tubular body 10. After the workpiece 36 has been steamed for the desired length of time, it may be removed and bent into the desired shape. Experience has shown that a material steaming apparatus of the present invention is efficient in operation and may be quickly and easily transported to any desired location.

While it will be apparent that the preferred embodiments of the invention herein disclosed are well calculated to fulfill the objects above stated, it will be appreciated that the invention is susceptible to modification, variation and change without departing from the proper scope of fair meaning of the subjoined claims. As, for example, instead of the electrical heating coil another type of heating means could be used, as a blow torch or the like.

What I claim is:

1. A material steaming apparatus of the class described, comprising: an elongated tubular body having an open front end; cap means releasably mounted on the open front of said body for enclosing the same; swingably

5 mounted leg means for supporting the tubular body in a downwardly and forwardly sloping position; a steam generating tube connected to said tubular body and depending therefrom adjacent the front end thereof and adapted to hold water for conversion to steam for transmission into said body; heating means connected to said steam generating tube; work support means for supporting material in said tubular body in spaced apart relationship thereto for steaming purposes; said cap means including a spring means on the outer side thereof; and, a swingably mounted retainer means connected to said body and engageable with said spring means for retaining said cap means in place.

2. A material steaming apparatus of the class described, 15 comprising: an elongated tubular body having an open front end; cap means releasably mounted on the open front of said body for enclosing the same; swingably mounted leg means for supporting the tubular body in a downwardly and forwardly sloping position; a steam generating tube connected to said tubular body and depending therefrom adjacent the front end thereof and adapted to hold water for conversion to steam for transmission into said body; heating means connected to said steam generating tube; work support means for supporting material in said tubular body in spaced apart relationship thereto for steaming purposes; and cap means including a spring means on the outer side thereof; a swingably mounted retainer means connected to said body and engageable with said spring means for retaining said cap 20 means in place; said work support means including a plurality of supporting members with each of said supporting members being formed to mate with and be supported by the inner surface of said tubular body, and the upper end of said supporting members being formed 25 to releasably hold a workpiece thereon.
